OBJECT SUPPORTING MEANS

Edward F. Mayer, Kellogg, Idaho

Application November 14, 1933, Serial No. 698,009

1 Claim. (Cl. 248—1)

The present invention relates to air operated figures or devices which are adapted to be positioned on an automobile where the movement of the air causes the figure or device to have certain motion imparted thereto.

An important object of the invention resides in the provision of a novel form of device or figure which is adapted to be positioned on the hood of an automobile without interfering with the automobile in any way.

Another very important object of the invention resides in the provision of a device of this nature which is simple in its construction, inexpensive to manufacture, easy to mount in place and remove, thoroughly efficient and reliable in use and operation, and otherwise well adapted to the purpose for which it is designed.

With the above and numerous other objects in view as will appear as the description proceeds the invention consists in certain novel features of construction, and in the combination and arrangement of parts as will be hereinafter more fully described and claimed.

In the drawings:

Figure 1 is a fragmentary side elevation of an automobile showing my device mounted on the hood thereof.

Figure 2 is a front elevation of the device showing the hood in section.

Figure 3 is a top plan view of the device.

Figure 4 is a vertical section through the device taken substantially on the line 4—4 of Figure 2.

Figure 5 is a vertical section through the device taken substantially on the line 5—5 of Figure 4.

Figure 6 is an enlarged detail top plan view of the device.

Figure 7 is a vertical section through the tubular standard.

Figure 8 is a plan view of a block.

Figure 9 is a detail elevation of the crank shaft, and

Figure 10 is a perspective view of one of the hooks.

Figure 11 is a detail sectional view showing how an arm is connected with the body of the figure.

Referring to the drawings in detail it will be seen that the numeral 5 denotes a base provided on its bottom with felt sheet 6 or the like to prevent scratching of the hood. On each side of the base there are attached the two ends of a cord 7 by suitable means 8 adjacent the ends of said base. Numerals 9 denote straps in loop formation and adjustable by means of a buckle structure 11. The straps 9 are preferably possessed of elasticity. The intermediate portions of the cords 7 pass through openings in the straps. Snap fasteners 12 on the straps are engaged with hooks 14 which are engageable under the free

edges of the hood as best illustrated in Figure 2 thereby holding the base centrally located on top of the hood.

A hollow standard 15 is mounted in the center of the base and rises therefrom. Numeral 16 denotes a hollow doll like transparent figure through an opening in the bottom of which the standard 15 projects terminating a slight distance from the top of the figure. A bracket 17 is mounted on the standard 15 in the head of the 10 Figure 16 and has a socket for supporting an electric bulb 18. Wiring 19 for the electric bulb passes through the hollow standard 15 and also through a groove in the bottom of the base as shown to advantage in Figure 5 so as to be connected up with the battery of the automobile.

Numeral 20 denotes a block fixed on the standard 15 and having ears 21 bent upwardly alongside the bottom of the figure as shown to advantage in Figure 5 and this block is disposed above 20 a block 22 on the standard 15.

A shaft 23 is journaled across the Figure 16 and has cranks 24 on the ends thereof pointing in opposite directions. Arms 25 are fixed on these cranks and have fins or blades 26 fixed thereon 25 so that when the automobile moves the air currents set up thereby will cause the rotation of the shaft 23.

It is thought that the construction, operation, utility and advantages of this invention will now be quite apparent to those skilled in this art 30 without a more detailed description thereof.

The present embodiment of the invention has been described in considerable detail merely for the purposes of exemplification since in actual 35 practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I 45 claim as new is:

Means for supporting an object on the hood of a motor vehicle comprising an object carrying base adapted to rest on a portion of the top of the hood, a pair of cords having their ends connected to opposing side edges of said base and extending downwardly over the side portions of said top portion, a pair of straps, each adjustable as to its length and each having a hole in its upper end through which a cord passes with 50 sliding movement and a hook connected with the lower end of each strap and adapted to engage the lower edge of each movable member of the hood.

EDWARD F. MAYER.
